UNITED STATES PATENT OFFICE.

WALTER FRITZ, OF BERLIN, GERMANY.

MARINE TURBINE.

1,073,895.

Specification of Letters Patent. Patented Sept. 23, 1913.

Application filed May 17, 1911. Serial No. 627,783.

To all whom it may concern:

Be it known that I, WALTER FRITZ, engineer, a subject of the German Emperor, and residing at Berlin, Germany, have invented

5 certain new and useful Improvements in Marine Turbines, of which the following is a specification.

My invention relates to marine turbines in which the axial thrust is relieved.

10 It is well-known in connection with high-pressure marine turbines of the drum type that the axial thrust due to the steam acting on the blades, if entirely exerted in one direction, greatly exceeds the propeller thrust.

15 Various proposals have been made for balancing the thrust, including the use of dummy pistons, and forward flow of steam over a portion of the drum, and in connection with turbines for other than marine 20 purposes it is usual to balance or partly balance the thrust by having a high pressure and a lower pressure over which the steam flows in opposite directions. But in connection with marine engines, where there is an

25 astern turbine in the same casing with the ahead turbine, this latter arrangement has the disadvantage that there must be at least one stuffing box, capable of withstanding high pressure, inaccessible in the interior 30 of the casing (for the first stage of either the ahead or astern turbine). For efficient working the use of labyrinth packing is indicated, and considerable loss of steam is involved by the comparatively large clearance 35 which experience has shown to be necessary with internal stuffing boxes for lightly built marine turbines.

An important object of my invention is 40 to obviate this disadvantage and to enable both the high pressure stuffing boxes for the first stages of the ahead and astern turbines to be external and easily renewable, and therefore designed with small clearance, involving much less loss of steam than a 45 labyrinth packing placed under similar conditions inside the casing.

To this end I provide at least three ahead 50 turbine drums, whereof two are acted on by steam flowing astern, the third being acted on by steam flowing forward, the pressures and diameters being so proportioned that the propeller thrust and the collective thrust of the drums are wholly or partly balanced, and the relative arrangement of 55 the three drums or stages being such that high pressure packing is only required at

the end of the casing, the internal packing having to withstand only comparatively low pressure. The astern turbine may be of similar or different design.

60

Figure 1 is a longitudinal sectional view of a turbine embodying one form of my invention. Fig. 2 is a similar view embodying another form of my invention.

Referring in the first place to Fig. 1, *a* is the main inlet, whence the steam acts on the blades of the first drum or stage *b*. It will be understood that the latter may be subdivided, that is to say there may be a plurality of rotors *b* in series. From the drum *b* the steam flows through a channel *c* to the second stage, or drum *d*, over which it flows in the opposite direction, and thence through channel *e* to the third drum *f*, over which it flows in the same direction as over the drum *b*. It is an essential characteristic of this arrangement that the drums *b* and *d* are traversed in series. The drums are so proportioned that their residual axial thrust is approximately equal to the propeller thrust, but oppositely directed, so that there is but slight pressure on the thrust collars *p*. The stuffing box *g*, subject to the highest pressure, is outside the casing, and easily accessible. The stuffing boxes *h* and *i* inside the casing are subject to much smaller pressure differences, and the loss of steam through them is, therefore, only small. The astern turbine *m*, open to the vacuum chamber *k* and exhaust *l*, is supplied with steam at *n*, so that the packing for the first stage of the astern turbine is also at the end of the casing.

In the case of large marine engines it is usual to have separate high pressure and low pressure casings, the low pressure casing containing an ahead and an astern turbine, an axially movable clutch being frequently provided between the casings. Inasmuch as the propeller thrust cannot be transmitted by this clutch, I prefer, in such an arrangement, to have two drums in the high pressure casing, traversed in opposite directions by steam, so as to nearly balance each other, the pressure on the ahead drum in the low pressure casing being proportioned and directed so as to partly or wholly balance the propeller thrust. In this arrangement the high pressure packings are also at the ends of the casings, as will be seen by reference to Fig. 2 of the drawing. Steam taking the path *a*, *b*, *c*, *d*, flows in

opposite directions over the drums *b* and *d* in the high pressure casing, so that there is practically no thrust from the high pressure shaft to the thrust bearing *p*. After flowing through the pipe *e* the steam flows astern over the low pressure drum *f*, the axial thrust of which nearly balances the propeller thrust, so that there is but slight pressure at the thrust-bearing *g*. The axial 5

30
ally movable clutch *r* allows of adjusting end play of the high and low pressure shafts, without additional strains on the thrust collars *p* and *g*. The arrangement of the astern turbine *m* is the same as in Fig. 1. The internal stuffing-box *h* of small diameter is subject to only comparatively small pressure difference, the high pressure stuffing boxes *g*, *i*₁, *i*₂, and *o* being external and easily accessible.

1. In a marine turbine engine, the combination with a shaft, of three ahead turbine drums on the shaft, an astern drum on the shaft, a casing having two inlets, an exhaust and channels for causing steam flowing astern to act on two of the ahead turbine drums and steam flowing ahead to act on the third ahead drum and on the astern drum, the first stages of the ahead and the astern drums being at the ends of the turbine engine.

2. A thrust neutralizing marine turbine construction comprising in combination, a series of three ahead turbines with the high

pressure turbine of the series disposed forward and the intermediate and low pressure turbines disposed successively rearward, guiding means causing the steam to traverse the intermediate turbines in a direction reverse to the direction of flow through the high and low pressure turbines, an astern turbine in the rear of the low pressure turbine and having a steam flow in a direction reverse to the astern thrust of the propeller, and outlet means common to the low and astern turbine, substantially as described.

3. A thrust neutralizing turbine construction comprising in combination, a series of three ahead turbines with the high pressure turbine of the series disposed forward and the intermediate and low pressure turbines disposed successively rearward, guiding means causing the steam to traverse the intermediate turbine in a direction reverse to the direction of flow through the high and low pressure turbines, and an astern turbine in the rear of the low pressure turbine and having a steam flow in a direction reverse to the astern thrust of the propeller, substantially as described.

In testimony whereof I have signed my name to this specification in the presence of two witnesses.

WALTER FRITZ.
